UNITED STATES PATENT OFFICE.

GOTTLIEB GEIGER, OF CLEVELAND, OHIO.

LIFE-GUARD FOR RAILWAY-CARS.

SPECIFICATION forming part of Letters Patent No. 746,692, dated December 15, 1903.

Application filed October 5, 1903. Serial No. 175,717. (No model.)

To all whom it may concern:

Be it known that I, GOTTLIEB GEIGER, a citizen of the United States of America, and a resident of Cleveland, in the county of Cuyahoga and State of Ohio, have invented certain new and useful Improvements in Life-Guards for Railway-Cars, of which the following is a specification.

This invention relates to life-guards for railway-cars; and it consists in the new and improved constructions and combinations of the elements comprising such mechanisms, substantially as hereinafter described, and pointed out in the claims.

15 The invention has for its object to provide a double or tandem life-guard—that is, one guard to follow the first, so that in case the first does not pick up the object on the track the second will, the operations of the two 20 guards being automatic.

A further object is to provide a means attached to the forward guard whereby a person or article caught upon the forward guard will not be jarred or jolted off, but will be retained thereon.

25 A further object is to provide a cushioning device located above the forward guard and extending across the front of the car and designed to avoid the shock to a person picked 30 up by the forward guard and striking against the front of the car.

The invention also consists in other features of improvement.

To accomplish these objects, I construct the 35 forward guard with a locking device whereby the guard shall be held up from the road-bed, but may be easily and quickly unlatched by the motorman for dropping it to the road-bed in case a person or object is on the track. 40 I also provide a second or tandem guard, also locked to be held up from the roadway, but may be readily unlocked to fall by the upward movement of the forward guard in case the forward guard should not catch the person or object, but should be lifted and pass 45 over the person or object, thereby being in position to catch when the forward guard fails.

The nature and performance of these improvements will fully appear when considered in connection with the accompanying drawings, in which—

Sheet 1, Figure 1, is a top or plan view of my new improvements in life-guards for railways. Sheet 2, Fig. 2, is a front end elevation of the same. Fig. 3 is also a front end 55 elevation of the same with the forward guard and the cushioning device removed. Sheet 3, Fig. 4, is a side elevation of the life-guard mechanism. Fig. 5 is an inside view of one of the hangers for supporting the guard mechanism, showing the locking and releasing devices.

In the drawings, A represents the floor of a car.

B B are brackets secured to the under side 65 of the floor and which support and carry all of the guard mechanisms.

C C are plates attached to the brackets by means of bolts b b passed through slots in the brackets, whereby the plates may be adjusted 70 at such heights as the conditions of the car may require.

D D are angle-levers suspended at their angles to front ends of the said plates B B by means of the cross-rod d.

To the lower ends of the levers D D is attached the forward life-guard G, consisting of a framework of rods constructed in about the usual manner. The inner end of said guard is supported on two cross-rods g g, extending across between the levers D D. To the forward guard is provided a self-acting fender to prevent a body having been caught from being jarred or jolted off again. It consists of a wire frame or bow E, having its 85 forward member lying across and over the forward cross-bar of the guard G, it being held in its place by being passed through loops or eyes e e at the forward corners of the guard. The side members of said fender extend along the sides of the guard and have their ends secured to levers F F on the cross-rod g at the inner end of said guard G. Said levers are provided with springs f f, which serve to throw the lower ends of said levers 90 forward, and thereby carry the fender forward and upward, as shown in the dotted lines in Fig. 4.

To retain the fender E in its rearward position, I provide a latching device consisting 100 of a wire frame or bow H, having its ends secured to the forward cross-bar of the guard

G and its rear corners caught in notches *h h* in the lower ends of the levers F F.

I is a cross-rod attached to the side members of the latch-frame H and extending across 5 and over the guard G, as seen in Figs. 1 and 4. By means of this latch-frame whenever a body is caught on the guard the body will push down upon the cross-rod I, and thereby release the levers F F. This will instantly 10 cause the fender E to be thrown forward and upward in front, and thereby supply a means of preventing the body from being again dislodged from the guard.

I also provide a locking device for holding 15 the forward guard G upward away from the road-bed, consisting as follows: To the inside faces of the plates C C are placed latch-bars J, (seen in Fig. 5,) held to slide in bearings K. The forward ends of said latch-bars engage 20 with notches on the inner ends of the levers D D for holding the guard G upward in the position seen in Fig. 4. For withdrawing said latches when desired a cross-rod L is journaled in the plates C C, having 25 a crank-arm M engaging in between two pins *m m* on said latch-bar J. N is also a crank-arm on said cross-rod L, to the moving end of which is attached a vertical rod O, extending upward through the floor of the car 30 and in such position that the motorman can readily press upon it with his foot whenever occasion requires for dropping the guard G.

A rear or second guard P is pivotally suspended from the rear ends of the plates C C 35 and is held in the upward position by means of latch-levers P', fulcrumed onto the sides of the bearings K. The rear end of said latch-levers P' engage with notches *p* in the upper ends of the side bars of the rear guard 40 P and hold the guard up from the road-bed. The forward ends of said latch-levers P' are curved downward and may be depressed by means of pins Q on the levers D D. Springs S hold the rear ends of the latch-levers down 45 in their engagement with the notches *p* of guard P, and springs S', attached to crank-arms M, serve to hold the latches J forward in place and also hold the push-rod O up. This method of releasing the rear guard P is intended 50 as an emergency safeguard, as in case that the forward guard should be lifted by a body instead of picking it up the levers D D will depress the latch-levers P', and thereby release the rear guard P, when said guard 55 will immediately drop into place for catching the body missed by the forward guard. The lifting of the front end of guard P will again latch itself. The forward guard may be turned entirely upright without deranging 60 the latch or locking mechanisms.

The cushioning device consists as follows: R R are two upright brackets attached to the front end of the car-floor, having sockets *r r* for supporting a curved spring-cushion T, 65 consisting of bent leaf steel springs, the ends of which are firmly secured to a cross-rod *t*,

that will rest in the sockets *r r*. The other and lower ends of the springs are also firmly attached to a cross-rod U, which slidably lies on the top edges of the plates C C. To said 70 lower cross-rod U are pivotally attached two rods V V, upon which are placed spiral springs *z z*, and said rods V V are passed through eyes *x x* on the lower ends of the two brackets R R beneath the floor of the 75 car. These springs *z z*, together with the leaf-springs T, supply a perfect cushion for avoiding a shock to the person or body striking against the front of the car. The spiral springs on the rods V V bear against the 80 eyes *x x* and serve to hold the cushion out in its normal position, as shown in Fig. 4, but yielding readily to the pressure of a body striking against it.

From the foregoing it will be seen that a 85 body picked up by the forward guard will be retained thereon by the automatic operation of the fender, and should the body be not picked up the guard would be lifted by running up onto the body. This would immediately cause the rear guard to drop and pick up the body, and should the body be caught up with force it would strike against the cushion, then the force would be broken and fall easily onto the guard, and the fender 95 would retain it thereon.

Having described my invention, what I claim is—

1. In life-guards for railway-cars, the combination with the forward guard of the body-retaining device consisting of a fender-frame extending across the front of the guard, its side members attached to spring-actuated levers on the rear cross-bar of the guard, a similar latch-frame attached to the forward 100 cross-bar of the guard and having its rear member engaging with notches in said spring-actuated levers, and adapted for freeing the fender-frame by the falling of a body onto the latch-frame being caught on the said forward guard, substantially as described.

2. In a life-guard for railway-cars the combination with the car of suspending-brackets, plates attached to said brackets and having vertical adjustment, guard-carrying angle-bars pivotally supported at forward ends of said plates, latch-bars on said plates and engaging with the inner ends of said angle-bars, a cross-rod journaled between said plates, crank-arms on said cross-rod engaging with the latch-bars, and a crank-arm on said cross-rod and a vertical rod connected to said crank-arm, and extending upward through the floor of the car, adapted for withdrawing said latch-bars, by the pressure 115 of the motorman's foot, for dropping the forward guard, substantially as and for the purpose set forth.

3. In life-guards for railway-cars, the combination with the car, of a cushioning device, 120 consisting of brackets attached to the front end of the car-platform, a cross-rod supported

by said brackets, curved leaf-springs having their upper ends attached to and held by said cross-rod, a cross-rod loosely lying on the top edges of the plates C C and having 5 the lower ends of the leaf-springs attached thereto, rods pivotally attached to said lower cross-rod and extending back and slidably supported in eyes under the car-platform, springs on said rods bearing against the said

eyes, and adapted to operate substantially in the manner and for the purpose set forth.

Signed by me at Cleveland, Ohio, this 2d day of October, 1903.

GOTTLIEB GEIGER.
